UNITED STATES PATENT OFFICE.

IVER STOKKE, OF SIOUX FALLS, SOUTH DAKOTA.

COMPRESSED-AIR-VALVE DIAPHRAGM.

1,353,290.

Specification of Letters Patent. Patented Sept. 21, 1920.

Application filed May 7, 1917. Serial No. 167,111.

To all whom it may concern:

Be it known that I, IVER STOKKE, a citizen of the United States, resident of Sioux Falls, in the county of Minnehaha and State of South Dakota, have invented a new and useful Compressed-Air-Valve Diaphragm to be Used in Connection With Thermostatic Temperature Control, of which the following is a specification.

10 This invention relates to certain new and useful improvements in heat regulators and primarily to an improved compressed air, valve-controlling device for opening and closing the valve which controls the admission of the heating fluid to a radiator, said device to be employed in connection with a thermostatic temperature control by which the temperature of a room may be kept uniform in an automatic manner.

20 The principal object of this invention is to provide an improved valve control which will be efficient in operation, very sensitive to the change of temperature, and yieldable and resilient connection between the valve stem and the diaphragm or piston of the control device, said piston being reversible to vary the size of the compressed air chamber within the device and thereby increase its field of utility and adaptability.

30 Further, the invention resides in the features of construction and the arrangements and combinations of parts hereinafter described and claimed, reference being had to the accompanying drawing wherein

35 Figure 1 is a side elevation of the improved device;

Fig. 2 is a sectional view thereof with the pipe connection for the usual thermostatic temperature control.

40 Referring more in detail to the drawings with like characters of reference for corresponding parts throughout the several views, the casing or cylinder 1 is cup-shaped, providing an air chamber 2 in which the reversible piston 3 is slidably mounted. The opened lower end of the casing is counterbored to form an internal seat 4 for packing 5 about the piston or diaphragm member 3, said packing being retained and compressed on its seat by an upwardly projecting annular extension 6 on the spider formed housing or covering 7 for the lower opened end of the inverted cup-shaped casing. Said casing and housing are detachably clamped together by

screws 8 that are passed through the peripheral flanges 9 and 10 formed on said parts.

The closed upper end wall of the casing is provided with a small port 11 through which communication with chamber 2 may be obtained. A pipe section 12 is threaded in the boss 13 about said port and this section is connected to the usual thermostatic temperature control (not shown) by pipe 65 section 14 and elbow 15 in which latter is arranged a strainer 16 for preventing the passage of all impurities that might interfere with the efficient operation of the device. This strainer is preferably a piece of 70 cotton which is retained within the elbow by the perforated disks 17.

The spider 7 is formed with a central collar 18 which acts as a guide for the stem 19 of the radiator valve not shown. A coiled 75 spring 20 is interposed between the valve stem 19 and the piston 3, seating at its lower end on the upper end of said stem and finding a bearing at its opposite end in sockets 21 or on the end wall of the axial projection or boss 23.

Should it be desired to lock the radiator valve either opened or closed against the action of the piston 3, this may be accomplished by binding a set screw against valve 85 stem 19 to hold it fixed, said set screw being threaded radially through hole 24 in the collar 18.

In practice, as the air pressure, admitted into chamber 2 by the thermostatic temperature control (not shown), strikes the upper surface of the piston and forces it down, it forces the coiled spring together, or contracts the same, and as the air pressure releases, the coiled spring extending will force 95 the piston upwardly, thus opening and closing the valve to which it is attached.

The piston may be reversed to vary the size of the chamber 2, as well as to accommodate for different lengths of springs, in 100 which connection it will be noted that the skirt 25 of the piston is sufficiently long to operate within the cylinder in either disposition of said piston.

The coiled spring 20 between the piston 105 and valve stem constitutes a resilient connection which permits relative movement between said connected parts, which is very desirable and essential in the pneumatic type of valve control since the piston may con- 110

tinue to move even though the valve be seated. Consequently, the valve is never jammed on its seat nor otherwise injured and rendered inefficient.

5 What is claimed is

1. A fluid operated valve control comprising an inverted cup-shaped casing having a fluid passage leading through its closed top and being counterbored about its open lower 10 end to form an annular seat, packing disposed on the seat, a clamp ring drawn onto the packing and provided with a cylindrical extension internally flared in a downward direction and suspending a guide member 15 therefrom by connecting arms, a valve stem slidable through the guide member, a piston operable in the casing and over the packing and formed with a skirt depending about the valve stem, and a spring housed within 20 the piston skirt and seating at one end on the piston and at its opposite end on the valve stem.
2. A fluid operated valve control comprising an inverted cup-shaped casing having a fluid passage leading through its closed top and being counterbored about its open lower 25 end to form an annular seat, packing disposed on the seat, a clamp ring drawn onto the packing and provided with a cylindrical 30 extension internally flared in a downward

direction and suspending a guide member therefrom by connecting arms, a valve stem slidable through the guide member, means carried by the guide member for locking the valve stem against movement, a piston operable in the casing and over the packing and formed with a skirt depending about the valve stem, and a spring housed within the piston skirt and seating at one end on the piston and at its opposite end on the valve 35 stem.

3. A fluid operated valve control comprising, in combination with the stem of a valve, a casing having a fluid chamber, a reversible piston slidable therein, a housing secured to 45 the casing over the piston and formed with an opening through which the valve stem is guided, and a coiled spring interposed between the piston and valve stem and housed by the piston, when in one position, and exposed, when reversed.

4. A fluid operated valve control comprising a casing, a reversible cup-shaped piston slidable therein and provided in the opposite sides of the bottom of said cup-shaped 55 piston with bearings, and resilient means engaging in the outer bearing for connection at its opposite end to the stem of a valve.

IVER STOKKE.
